(57) **CLAIM**

The ornamental design for a combined hanger tie with hangers, as shown and described.

DESCRIPTION

FIG. 1 is a front perspective view of combined hanger tie with hangers showing my new design;

FIG. 2 is an enlarged front elevational view of a front end of the hanger tie of FIG. 1;

FIG. 3 is a rear perspective view of the combined hanger tie with hangers of FIG. 1;

FIG. 4 is a front elevational view of a back end of the hanger tie of FIG. 1;

FIG. 5 is an exploded front perspective view of the combined hanger tie with hangers of FIG. 1; and,

FIG. 6 is an exploded perspective view of the tie hanger. The hanger tie is shown separately in FIGS. 2, 4, and 6 for clarity of illustration.
